by the Secretary of the Navy

Application May 23, 1944, Serial No. 536,967

2 Claims. (Cl. 250—36)

1

This invention relates to a linear sawtooth generator.

In the past, most sawtooth generators have utilized the charging or polarizing current of a resistance to establish the slope of the sawtooth. All such charging or polarizing currents have been found to vary with time, and various means have been proposed to eliminate this variation, with its consequent impairment of the linearity of the sawtooth. Previous generators have sometimes utilized the high variational resistance of the plate circuit of a pentode vacuum tube to minimize this variation, but with only a limited degree of success. Other attempts have been made to utilize nonohmic resistors, such as varistors and thermistors, to obtain such high variational resistance, and thus a constant current charging or polarizing circuit.

It is the purpose of the present invention to utilize vacuum tube amplification to multiply the variational resistance of a pentode constant current tube by a large factor.

Thus, one of the objects of the invention is to provide a voltage which varies linearly with respect to time.

Another of the objects of the invention is a means for providing a convenient and accurate time base for measurement and indication of functions varying with time.

A further object of the invention is a linear sawtooth generator which may be conveniently used to measure time in such applications as television scanning circuits, cathode-ray oscilloscopes, chronographs, radio and sound-ranging systems, frequency meters, and any other device in which such a time base is necessary.

A further object of the invention is a linear sawtooth generator in which a constant current source is utilized to charge a capacitor, which capacitor is then discharged through a gaseous discharge tube.

Still another object of the invention is a means for maintaining constant current in a circuit element having variable characteristics.

The drawing is a schematic diagram of a circuit embodying the present invention.

The circuit arrangement of the figure shows a method of obtaining a low-frequency asymmetrical sawtooth wave characterized by a rise in voltage that is substantially linear with respect to time, followed by a rapid drop in voltage to the starting point. The rapid drop, or flyback, lasts for a small fraction of the total sawtooth cycle.

The linear rise in voltage, with respect to time, is achieved by charging a condenser from a high

2

voltage power supply through a constant current, non-ohmic resistance. The rapid drop in voltage, or flyback, is obtained by suddenly discharging the previously charged condenser through a gaseous discharge tube.

Referring to the drawing, capacitor 1 is charged from the power supply terminals through resistor 2, vacuum pentode 3 and rheostat 4. During the charging phase of the sawtooth cycle, the gas triode 5 is non-conducting, being biased past cut-off by a voltage derived from potentiometer 6. When the charging voltage across capacitor 1 rises to a value equal to the predetermined breakdown voltage of gas triode 5, conduction is established which rapidly discharges capacitor 1, reducing the voltage across capacitor 1 to the extinction voltage of gas triode 5, at which point it becomes non-conducting and the charging phase of the cycle repeats.

When a capacitor is charged from a constant resistance source of voltage, the charging current decreases exponentially with time. Since the slope of the voltage-time curve is proportional to the charging current as the charging current approaches zero, the slope of the voltage-time curve also approaches zero. In the circuit shown, the vacuum pentode 3 and its associated circuit components are arranged to prevent the charging current in capacitor 1 from varying exponentially with time; and instead, force the charging current to remain constant. By thus forcing the charging current to remain constant it is found that the voltage across capacitor 1 increases linearly with time during the charging phase of the cycle. The arrangement to thus maintain constant the charging current through capacitor 1 is accomplished by vacuum pentodes 3, 7 and associated resistors and voltage dividers.

Vacuum pentode 3 is a high resistance, high mu, radio-type, pentode similar to types 6J7 or 6SJ7. This tube has a high variational plate resistance which tends to resist any change in its plate current. As the charging current of capacitor 1 passes through the plate resistance of vacuum pentode 3, this high variational plate resistance minimizes charging current variations.

This inherently high variational plate resistance of vacuum pentode 3 while useful, is not high enough to maintain the charging current of capacitor 1 sufficiently constant to obtain satisfactory linearity (with respect to time) of the output voltage. The addition of vacuum pentode 7 to the circuit multiplies the effective variational plate resistance of vacuum pentode 3 by a large factor.

Vacuum pentode 7 is a tube of the same type as

vacuum pentode 3. Both tubes 3, 7 obtain their screen grid voltage from a tap on the voltage divider made up of potentiometer 6 and resistors 8 and 9. The static control grid voltage on vacuum pentode 3 is established by a tap on the voltage divider and coupling circuit made up of resistors 10, 11 and 12. The cathode voltage on vacuum pentode 3 is established by rheostat 4, and the cathode voltage on vacuum pentode 7 is established by a tap at the junction of resistors 8 and 9 on the voltage divider made up of potentiometer 6 and resistors 8 and 9.

The operation of the constant current portion of the circuit can be described by assuming a small variation in the charging current to capacitor 1 and then examining, step by step, how the circuit opposes this change. Assume that capacitor 1 is being charged from the external voltage source, and, for example, that the charging current is decreased. It can be seen that resistor 2, rheostat 4 and the plate circuit of vacuum pentode 3 are all in series with the charging circuit to capacitor 1. Therefore, a decrease in charging current will decrease the voltage drop across rheostat 4 which makes the control grid of vacuum pentode 7 negative with respect to its cathode. This will tend to reduce the plate current flowing through vacuum pentode 7 which will in turn reduce the voltage drop through resistor 10 and thus make the potential at the plate of vacuum pentode 7 more positive with respect to ground. This rise in positive voltage at the plate of vacuum pentode 7 is coupled to the control grid of vacuum pentode 3 through the coupling resistor 11 which produces a positive excursion of the control grid of vacuum pentode 3. Making this control grid more positive acts to increase the plate current of vacuum pentode 3, which tendency opposes the decrease in charging current which initiated the above described train of events. Likewise, if the charging current had increased, all of the effects described would have operated in the opposite sense, and the grid of vacuum pentode 3 would have been driven somewhat negative to reduce the plate current of vacuum pentode 3, thus resisting the initial change in charging current.

It should be noted that both the sawtooth amplitude and sawtooth frequency are adjustable so that the invention may be adapted for any desired purpose.

The output amplitude of any relaxation oscillator depends on the voltage difference between breakdown and extinction in the gaseous discharge tube used to discharge its associated capacitor. In this invention the gaseous triode 5 is used to discharge the capacitor 1. Its extinction is not adjustable but its breakdown voltage can be set at any desired value by means of potentiometer 6, which controls the grid voltage of gaseous triode 5.

The frequency of the sawtooth is in turn determined by its amplitude and the slope of the voltage-time curve. As has been described, the amplitude is controlled by the characteristics of gas tube 5 and the setting of potentiometer 6; and the slope of the voltage-time curve is determined by the capacitance of capacitor 1 and the plate current of tube 3, in a manner that it is proportional to said current and inversely proportional to said capacitance. Since the current may easily be controlled by the setting of rheostat 4,

the frequency of the sawtooth may thus be varied at will.

It is seen that the present invention is extremely useful and has wide application.

As described it enables the production of linear sawtooth waves in a simple efficient manner. Additionally, it provides means for maintaining a constant current in a circuit or circuit element having variable characteristics. As such, the device is very useful in the measurement of high resistance since the current through the circuit is maintained at a constant value independently of the resistance of such circuit. The resistance of the circuit to be measured is proportional to the potential drop across said unknown circuit, and in fact, is equal to the ratio of the potential drop to the current flowing in it. This will provide ready means for constructing an "ohm meter" with a linear scale.

I claim:

1. A sawtooth voltage generator, comprising a first pentode tube having an anode, a cathode, and a control grid, a first resistor connected to said cathode, a power supply, a capacitor connected to be charged from said power supply through the tube and the resistor, a gaseous discharge device connected across the capacitor to discharge the same when a predetermined voltage is reached; a second pentode tube having an anode, a cathode, and a control grid, means including a second resistor connecting the anode of the second pentode to the positive side of the power supply, means connecting the cathode of the second pentode to the negative side of the power supply, means to apply to the control grid of the second pentode the potential variations at the high potential end of the first resistor, and means to apply to the control grid of the first pentode the potential variations at the low potential end of the second resistor.

2. A sawtooth voltage generator, comprising a pentode tube having an anode, a cathode, and a control grid, a first resistor connected to said cathode, a power supply, a capacitor connected to be charged from said power supply through the tube and the resistor, a gaseous discharge device connected across the capacitor to discharge the same when a predetermined voltage is reached; a second tube having an anode, a cathode, and a control grid, means including a second resistor connecting the anode of the second tube to the positive side of the power supply, means connecting the cathode of the second tube to the negative side of the power supply, means to apply to the control grid of the second tube the potential variations at the high potential end of the first resistor, and means to apply to the control grid of the pentode tube the potential variations at the low potential end of the second resistor.
